(57) **CLAIM**

The ornamental design for a one-piece scan bar for a loop hook, as shown and described.

DESCRIPTION

FIG. 1 is a perspective view of a first embodiment of a one-piece scan bar for a loop hook showing my new design with a scan plate affixed thereto;

FIG. 2 is a perspective view of the first embodiment thereof;
FIG. 3 is a right side elevational view of the first embodiment thereof;

FIG. 4 is a left side elevational view of the first embodiment thereof;

FIG. 5 is a rear elevational view of the first embodiment thereof;

FIG. 6 is a front elevational view of the first embodiment thereof;

FIG. 7 is a top plan view of the first embodiment thereof;

FIG. 8 is bottom plan view of the first embodiment thereof;

FIG. 9 is a perspective view of a second embodiment of a one-piece scan bar for a loop hook showing my new design with a scan plate affixed thereto;

FIG. 10 is a perspective view of the second embodiment thereof;

FIG. 11 is a right side elevational view of the second embodiment thereof;

FIG. 12 is a left side elevational view of the second embodiment thereof;

FIG. 13 is a rear elevational view of the second embodiment thereof;

FIG. 14 is a front elevational view of the second embodiment thereof;

FIG. 15 is a top plan view of the second embodiment thereof; and,

FIG. 16 is bottom plan view of the second embodiment thereof.

The portions shown in broken lines are included for illustrative purpose only and form no part of the claimed design.
